(57) **CLAIM**

We claim the ornamental design for a dispenser for food service equipment, as shown and described.

DESCRIPTION

FIG. 1 is a front perspective view from above of the claimed design;

FIG. 2 is a front view of the claimed design;

FIG. 3 is a rear view of the claimed design;

FIG. 4 is a right side view of the claimed design;

FIG. 5 is a left side view of the claimed design;

FIG. 6 is a top view of the claimed design; and,

FIG. 7 is a bottom side view of the claimed design.

The ornamental design that is claimed is shown in solid lines in the drawings. The broken lines shown are included for the purpose of illustrating the unclaimed portions of the article that form no part of the claimed design.
